UNITED STATES PATENT OFFICE

JOHN SPRING, OF NEW YORK, N. Y., ASSIGNOR TO THE BIGELOW CARPET COMPANY, OF MASSACHUSETTS.

DESIGN FOR CARPET.

SPECIFICATION forming part of Design No. 30,642, dated April 25, 1899.

Application filed March 31, 1899. Serial No. 711,290. Term of patent 3½ years.

To all whom it may concern:

Be it known that I, JOHN SPRING, a citizen of the United States, and a resident of the city, county, and State of New York, have invented a new and useful Design for Carpets, of which the following is a specification.

My design, as shown in the drawing, consists of a new design for a carpet.

The design is characterized by rows of composite elongated diamond-shaped figures and bold figures of greater breadth, also approximately diamond-like in outline, said figures being arranged alternately both lengthwise and crosswise of the carpet and disposed on a suitable background, which, moreover, is otherwise profusely decorated with smaller

figures of geometrical shapes, the bolder figure above mentioned reappearing frequently in smaller size. The whole is intended to present a characteristic rug-like appearance. 20

What I claim as new, and desire to secure by Letters Patent, is—

The design for a carpet substantially as shown and described.

In testimony whereof I have signed my 25 name to this specification in the presence of two subscribing witnesses.

JOHN SPRING.
